MOUNTING FOR HAND TELEPHONES

Herbert F. Obergfell, River Forest, Ill., assignor to
 Associated Electric Laboratories, Inc., Chicago,
 Ill., a corporation of Delaware

Application April 14, 1939, Serial No. 267,817

5 Claims. (Cl. 179—146)

The present invention relates to mountings for telephones and, more particularly, to desk mountings for hand telephones.

A mounting of this type conventionally comprises a supporting base, a pedestal carrying a calling dial, and a cradle provided with a switch-hook and adapted to support a hand telephone or hand set of the well-known Monophone type; the usual substation apparatus, including an induction coil, a condenser, a signal bell and a switching mechanism, being housed in the supporting base and pedestal of the mounting.

It is an object of the present invention to provide a mounting of the type described which is of simple and rugged construction and which embodies an improved arrangement for facilitating movement from place to place of the mounting and the hand telephone supported thereby.

The object set forth above is attained in accordance with the present invention by providing a mounting of the character described comprising a base, a pedestal and a cradle including two spaced-apart and upwardly extending cradle members, the pedestal including front and rear upwardly and inwardly extending walls and upwardly extending side walls formed by the cradle members. The rear wall of the pedestal and the cradle members are so constructed and arranged that a continuous substantially channel-shaped recess is provided in the top and rear of the pedestal, the cradle members being provided with aligned cradle seats therein adapted to support the handle of the hand telephone. First and second movable elements are provided which are carried by the mounting and disposed in the recess provided in the pedestal. More particularly, each of the elements is provided with a handle portion and extends between the cradle members and is pivotally mounted thereon immediately below the plane of the aligned cradle seats provided therein. The first element has a normal position wherein the handle portion thereof is disposed adjacent the rear wall of the pedestal and an operated position wherein the handle portion thereof is disposed away from the rear wall of the pedestal and rearwardly of the handle of the hand telephone; while the second member has a normal position wherein the handle portion thereof is disposed adjacent the top wall of the pedestal and an operated position wherein the handle portion thereof is disposed away from the top wall of the pedestal and forwardly of the handle of the hand telephone. The first and second elements are so constructed and arranged that the handle portions thereof are readily ac-

cessible when the first and second elements occupy their operated positions, thereby to accommodate movement from place to place of the mounting and the hand telephone supported thereby. Also, means is provided which is responsive to the movement of the first element from its normal position to its operated position for moving the second element from its normal position to its operated position. A member is carried by the first element which is effective to prevent a foreign object from being inserted between the rear wall of the pedestal and the first element when the first element occupies its operated position, thereby to prevent dislocation of the handle of the hand telephone from the aligned cradle seats provided in the cradle members incident to the movement from place to place of the mounting and the hand telephone supported thereby.

The novel features believed to be characteristic of the invention are set forth with particularity in the appended claims. The invention, both as to its organization and method of operation, together with further objects and advantages thereof, will best be understood by reference to the following specification taken in connection with the accompanying drawing, in which Figure 1 is a perspective view of a mounting for a hand telephone which is constructed and arranged in accordance with the present invention; Fig. 2 is a fragmentary longitudinal sectional view of the mounting shown in Fig. 1 and a hand telephone supported thereby, illustrating the normal positions of certain elements of the mounting; and Fig. 3 is a longitudinal sectional view of the mounting shown in Fig. 1 and a hand telephone supported thereby, illustrating the operated positions of the elements of the mounting and the substation apparatus housed therein.

Referring now more particularly to Figs. 1 and 3 of the drawing, there is shown a desk mounting or support 10 for a hand telephone or hand set of the well-known Monophone type illustrated at 11, which mounting comprises a supporting base 12, a pedestal 13, and a cradle 14 including two spaced-apart and upwardly extending cradle members 15 and 16. The pedestal 13 is provided with front and rear upwardly and inwardly extending walls 17 and 18, respectively, converging slightly forwardly of the cradle 14, a top wall 19 extending between the front and rear walls 17 and 18, respectively, and upwardly extending side walls formed by the cradle members 15 and 16. The top and rear walls 19 and 18, respectively, of the pedestal 13 and the cradle 14

members 15 and 16 are so constructed and arranged that a continuous substantially channel-shaped recess 20 is provided in the top and rear of the pedestal 13. Aligned cradle seats 21 and 5 22 are provided in the cradle members 15 and 16, respectively, the cradle seat 21 provided in the cradle member 15 being formed therein by spaced-apart and upwardly extending front and rear tines 23 and 24, respectively; and the cradle 10 seat 22 provided in the cradle member 16 being formed therein by spaced-apart and upwardly extending front and rear tines 25 and 26, respectively. The cradle seats 21 and 22 provided in the cradle members 15 and 16 are provided 15 with recesses therein into which two metal inserts 27 and 28, respectively, are securely positioned, the inserts 27 and 28 having openings therein into which two switchhooks or plungers 29 and 30, respectively, are slidably mounted.

20 The front wall 17 of the pedestal 13 is provided with an annular recess 17a therein within which a calling dial 31 is positioned and supported in place. The interiors of the supporting base 12 and the pedestal 13 are hollow in order to provide 25 a continuous cavity 32 therein which accommodates the usual substation apparatus, such as a signal bell 33, an induction coil 34, a condenser 35 and a switching mechanism 36, the switching mechanism 36 being operatively associated with 30 the switchhooks or plungers 29 and 30 by a suitable connecting lever mechanism 37. The opening into the cavity 32 formed in the supporting base 12 and the pedestal 13 is closed by a suitable base plate 38 fastened to the supporting base 12.

35 Also, the mounting 10 is so constructed and arranged that the center of gravity thereof is disposed in a substantially vertical plane extending through the aligned cradle seats 21 and 22 provided in the cradle members 15 and 16, respectively, in order to insure proper balance of the 40 mounting.

The handle of the hand telephone 11 is supported in the aligned cradle seats 21 and 22 provided in the cradle members 15 and 16, respectively, the weight of the hand telephone being adequate to retain the switchhooks or plungers 29 and 30 in their depressed positions against the bias of the switching mechanism 36, in order to retain the switching mechanism 36 in its open 50 circuit position in a well-known manner. When the handle of the hand telephone 11 is removed from the supporting cradle seats 21 and 22 provided in the cradle members 15 and 16, respectively, the switchhooks or plungers 29 and 30 are projected outwardly under the bias of the switching mechanism 36, in order to cause the switching mechanism 36 to be operated to its closed circuit position in a well-known manner.

In order to facilitate movement of the mounting 10 and the hand telephone 11 supported thereby from place to place, an arrangement is provided which comprises first and second elements 39 and 40 provided with handle portions 39a and 40a, respectively. The first element 39 is provided with two outwardly extending pivot pins 41 and 42 arranged in aligned openings provided in the inserts 27 and 28, respectively; while the second element 40 is provided with two outwardly extending pivot pins 43 and 44 arranged 55 in aligned openings provided in the inserts 27 and 28, respectively. Accordingly, the elements 39 and 40 are arranged in the recess 20 provided in the pedestal 13, extend between the cradle members 15 and 16 and are pivotally mounted in 70 the two sets of aligned openings provided in the

inserts 27 and 28 immediately below the plane of the aligned cradle seats 21 and 22 provided in the cradle members 15 and 16, respectively.

As best shown in Fig. 2, the first element 39 has a normal position wherein the handle portion 39a thereof is disposed adjacent the rear wall 18 of the pedestal 13; and the second element 40 has a normal position wherein the handle portion 40a thereof is disposed adjacent the top wall 19 of the pedestal 13. As best shown in Fig. 10 10 3, the first element 39 has an operated position wherein the handle portion 39a thereof is disposed away from the rear wall 18 of the pedestal 13 and rearwardly of the handle of the hand telephone 11; and the second element 40 has an 15 operated position wherein the handle portion 40a thereof is disposed away from the top wall 19 of the pedestal 13 and forwardly of the handle of the hand telephone 11.

The first element 39 carries an operating portion 45 which cooperates with an operating portion 46 carried by the second element 40, the operating portions 45 and 46 of the first and second elements 39 and 40, respectively, being so constructed and arranged that when the first 25 element 39 is rotated in a counterclockwise direction about the pivot pins 41 and 42, as viewed in Figs. 2 and 3, the operating portion 45 thereof engages the operating portion 46 of the second element 40, thereby to cause the second element 30 40 to be rotated in a clockwise direction about the pivot pins 43 and 44, as viewed in Figs. 2 and 3. In other words, when the first element 39 is operated from its normal position to its operated position, the second element 40 is operated from its normal position to its operated position due to the cooperation between the operating portions 45 and 46 of the first and second elements 39 and 40, respectively. Furthermore, it is noted that the movement of the first element 39 is positively arrested when this element is moved to its operated position by a pair of spaced-apart and aligned pins 39b carried by the cradle members 15 and 16; while the movement of the second element 40 is positively arrested when this element is moved to its operated position by a pair of spaced-apart and aligned pins 40b carried by the cradle members 15 and 16. The first element 39 is so constructed and arranged that the handle portion 39a thereof is readily accessible when the first element 39 occupies its normal position, thereby to accommodate movement of the first element 39 from its normal position to its operated position. The first and second elements 39 and 40, respectively, are also so constructed 50 and arranged that the handle portions 39a and 40a, respectively, thereof are readily accessible when the elements 39 and 40, respectively, occupy their operated positions, thereby to accommodate movement from place to place of the mounting 10 and the hand telephone 11 supported thereby.

A member 47 is pivotally mounted on the first element 39 adjacent the handle portion 39a thereof by a pivot pin 48, the member 47 being disposed between the first element 39 and the rear wall 18 of the pedestal 13. When the first element 39 is operated from its normal position to its operated position, the member 47 is rotated by gravity in a clockwise direction about the 65 pivot pin 48, as viewed in Figs. 2 and 3, into a substantially vertical position disposed between the first element 39 and the rear wall 18 of the pedestal 13. More specifically, the member 47 closes the opening between the first element 39 70 and

and the rear wall 18 of the pedestal 13 when the element 39 occupies its operated position, thereby to prevent a foreign object or the like from being inserted between the rear wall 18 of the pedestal 13 and the first element 39 when the first element 39 occupies its operated position. This arrangement prevents dislocation of the handle of the hand telephone 11 from the aligned cradle seats 21 and 22 provided in the cradle members 15 and 16 incident to the movement from place to place of the mounting 10 and the hand telephone 11 supported thereby.

The arrangement including the first and second elements 39 and 40 provides a convenient means for moving the mounting 10 and the hand telephone 11 supported thereby from one place to another. It is contemplated that a person wishing to move the mounting 10 and the hand telephone 11 supported thereby from one place to another will first grasp the handle portion 39a of the first element 39 with his fingers and exert a lifting force thereupon, in order to cause the first and second elements 39 and 40 to be operated from their normal positions to their operated positions as previously explained. The person will then grip the handle portion 40a of the second element 40 with his thumb, thereby to provide a convenient composite handle for moving the mounting 10 and the hand telephone 11 supported thereby from one place to another. Furthermore, when the first element 39 is moved from its normal position to its operated position, the member 47 is operated to close the opening between the first element 39 and the rear wall 18 of the pedestal 13, thereby to prevent the person from inserting his fingers between the first element 39 and the rear wall 18 of the pedestal 13 in order to insure that the handle of the hand telephone 11 is not dislocated from the cradle 14 of the mounting 10 incident to the movement thereof from one place to another.

In view of the foregoing, it is apparent that a desk mounting for a hand telephone is provided which is of simple and rugged construction and which embodies an improved arrangement for facilitating movement from place to place of the mounting and the hand telephone supported thereby.

While there has been described what is at present considered to be the preferred embodiment of the invention, it will be understood that various modifications may be made therein, and it is contemplated in the appended claims to cover all such modifications as fall within the true spirit and scope of the invention.

What is claimed is:

1. A mounting for a hand telephone, comprising a base, a pedestal, a cradle including two spaced-apart and upwardly extending cradle members, said cradle members being provided with aligned cradle seats therein adapted to support the handle of the hand telephone, said pedestal including front and rear upwardly and inwardly extending walls, a top wall extending therebetween and upwardly extending side walls formed by said cradle members, the top and rear walls of said pedestal and said cradle members being so constructed and arranged that a continuous substantially channel-shaped recess is provided in the top and rear of said pedestal, first and second movable elements carried by said mounting and disposed in the recess provided in said pedestal, each of said elements having a handle portion, said first element having a normal

position wherein the handle portion thereof is disposed adjacent the rear wall of said pedestal and an operated position wherein the handle portion thereof is disposed away from the rear wall of said pedestal and rearwardly of the handle of the hand telephone, said second element having a normal position wherein the handle portion thereof is disposed adjacent the top wall of said pedestal and an operated position wherein the handle portion thereof is disposed away from the top wall of said pedestal and forwardly of the handle of the hand telephone, said first element being so constructed and arranged that the handle portion thereof is readily accessible when said first element occupies its normal position, thereby to accommodate movement of said first element from its normal position to its operated position, said first and second elements being so constructed and arranged that the handle portions thereof are readily accessible when said first and second elements occupy their operated positions, thereby to accommodate movement from place to place of said mounting and the hand telephone supported thereby, and means responsive to the movement of said first element from its normal position to its operated position for moving said second element from its normal position to its operated position.

2. A mounting for a hand telephone, comprising a base, a pedestal, a cradle including two spaced-apart and upwardly extending cradle members, said cradle members being provided with aligned cradle seats therein adapted to support the handle of the hand telephone, said pedestal including front and rear upwardly and inwardly extending walls, a top wall extending therebetween and upwardly extending side walls formed by said cradle members, the top and rear walls of said pedestal and said cradle members being so constructed and arranged that a continuous substantially channel-shaped recess is provided in the top and rear of said pedestal, and said second movable elements carried by said mounting and disposed in the recess provided in said pedestal, each of said elements having a handle portion, said first element having a normal position wherein the handle portion thereof is disposed adjacent the rear wall of said pedestal and an operated position wherein the handle portion thereof is disposed away from the rear wall of said pedestal and rearwardly of the handle of the hand telephone, said second element having a normal position wherein the handle portion thereof is disposed adjacent the top wall of said pedestal and an operated position wherein the handle portion thereof is disposed away from the top wall of said pedestal and forwardly of the handle of the hand telephone, said first and second elements being so constructed and arranged that the handle portions thereof are readily accessible when said first and second elements occupy their operated positions, thereby to accommodate movement from place to place of said mounting and the hand telephone supported thereby.

3. A mounting for a hand telephone, comprising a base, a pedestal, a cradle including two spaced-apart and upwardly extending cradle members, said cradle members being provided with aligned cradle seats therein adapted to support the handle of the hand telephone, said pedestal including front and rear upwardly and inwardly extending walls, a top wall extending therebetween and upwardly extending side walls

formed by said cradle members, the top and rear walls of said pedestal and said cradle members being so constructed and arranged that a continuous substantially channel-shaped recess is provided in the top and rear of said pedestal, first and second movable elements carried by said mounting and disposed in the recess provided in said pedestal, each of said elements having a handle portion, said first element having a normal position wherein the handle portion thereof is disposed adjacent the rear wall of said pedestal and an operated position wherein the handle portion thereof is disposed away from the rear wall of said pedestal and rearwardly of the handle of the hand telephone, said second element having a normal position wherein the handle portion thereof is disposed adjacent the top wall of said pedestal and an operated position wherein the handle portion thereof is disposed away from the top wall of said pedestal and forwardly of the handle of the hand telephone, said first and second elements being so constructed and arranged that the handle portions thereof are readily accessible when said first and second elements occupy their operated positions, thereby to accommodate movement from place to place of said mounting and the hand telephone supported thereby, and a member carried by said first element for preventing a foreign object from being inserted between the rear wall of said pedestal and said first element when said first element occupies its operated position, thereby to prevent dislocation of the handle of the hand telephone from the aligned cradle seats provided in said cradle members incident to the movement from place to place of said mounting and the hand telephone supported thereby.

4. A mounting for a hand telephone, comprising a base, a pedestal, a cradle including two spaced-apart and upwardly extending cradle members, said cradle members being provided with aligned cradle seats therein adapted to support the handle of the hand telephone, said pedestal including front and rear upwardly and inwardly extending walls, a top wall extending therebetween and upwardly extending side walls formed by said cradle members, and first and second elements extending between said cradle members and pivotally mounted thereon immediately below the plane of the aligned cradle seats provided therein, each of said elements having a handle portion, said first element having a normal position wherein the handle portion thereof is disposed adjacent the rear wall of said pedestal and an operated position wherein the handle portion thereof is disposed away from the rear wall of said pedestal and rearwardly of the handle of the hand telephone, said second element having a

normal position wherein the handle portion thereof is disposed adjacent the top wall of said pedestal and an operated position wherein the handle portion thereof is disposed away from the top wall of said pedestal and forwardly of the handle of the hand telephone, said first and second elements being so constructed and arranged that the handle portions thereof are readily accessible when said first and second elements occupy their operated positions, thereby to accommodate movement from place to place of said mounting and the hand telephone supported thereby.

5. A mounting for a hand telephone, comprising a base, a pedestal, a cradle including two spaced-apart and upwardly extending cradle members, said cradle members being provided with aligned cradle seats therein adapted to support the handle of the hand telephone, said pedestal including front and rear upwardly and inwardly extending walls, a top wall extending therebetween and upwardly extending side walls formed by said cradle members, first and second elements extending between said cradle members and pivotally mounted thereon immediately below the plane of the aligned cradle seats provided therein, each of said elements having a handle portion, said first element having a normal position wherein the handle portion thereof is disposed adjacent the rear wall of said pedestal and an operated position wherein the handle portion thereof is disposed away from the rear wall of said pedestal and rearwardly of the handle of the hand telephone, said second element having a normal position wherein the handle portion thereof is disposed adjacent the top wall of said pedestal and an operated position wherein the handle portion thereof is disposed away from the top wall of said pedestal and forwardly of the handle of the hand telephone, said first element being so constructed and arranged that the handle portion thereof is readily accessible when said first element occupies its normal position, thereby to accommodate rotation of said first element from its normal position to its operated position, said first and second elements being so constructed and arranged that the handle portions thereof are readily accessible when said first and second elements occupy their operated positions, thereby to accommodate movement from place to place of said mounting and the hand telephone supported thereby, and means responsive to the rotation of said first element from its normal position to its operated position for rotating said second element from its normal position to its operated position.

HERBERT F. OBERGFELL.
